UNITED STATES PATENT OFFICE

166,801

COMBINATION HOSE AND SLIPPER-SOLE ASSEMBLY

Christopher Davidson, Eaton Rapids, Mich., assignor to John B. Davidson Woolen Mills, Inc., Eaton Rapids, Mich., a corporation of Michigan

Application February 10, 1950, Serial No. 7,859

Term of patent 7 years

(Cl. D47—7)

To all whom it may concern:

Be it known that I, Christopher Davidson, a citizen of the United States, residing at Eaton Rapids, Michigan, have invented a new, original, and ornamental Design for a Combination Hose and Slipper-Sole Assembly, of which the following is a specification, reference being had to the accompanying drawing, forming part hereof.

Figure 1 is a front perspective view of a combination hose and slipper-sole assembly showing my new design.

Figure 2 is a rear perspective view of the combination hose and slipper-sole assembly as seen from the opposite side of Figure 1.

The characteristic features of my design reside in the use of a toe cap and high heel counter for the combination hose and slipper-sole assembly, together with a type of stitching substantially as illustrated.

I claim:

The ornamental design for a combination hose and slipper-sole assembly, substantially as shown and described.

CHRISTOPHER DAVIDSON.
